UNITED STATES PATENT OFFICE.

LUCIEN H. HANDY, OF SAN FRANCISCO, AND CHARLES S. HOSFORD, OF BERKELEY, CALIFORNIA.

BURGLAR-ALARM AND DOOR-LOCK.

SPECIFICATION forming part of Letters Patent No. 700,039, dated May 13, 1902.

Application filed September 16, 1901. Serial No. 75,450. (No model.)

To all whom it may concern:

Be it known that we, LUCIEN H. HANDY, residing in the city and county of San Francisco, and CHARLES S. HOSFORD, residing at 5 Berkeley, county of Alameda, State of California, citizens of the United States, have invented certain new and useful Improvements in Burglar-Alarms and Door-Locks; and we do hereby declare the following to be a full, 10 clear, and exact description of the same.

Our invention relates to that class of burglar-alarms and door locks or checks in which an alarm mechanism is fitted to the door-casing or door when the latter is closed and is 15 adapted to be tripped or set in operation by the movement of the door in opening.

It consists in the novel construction, arrangement, and combination of parts, which we shall hereinafter fully describe and which 20 have for their object the provision of an inexpensive, portable, and effective device for giving security to occupants of rooms the doors of which are inadequately provided with fastenings.

25 Referring to the accompanying drawings, Figure 1 is a view of our device, showing it applied to a door. Fig. 2 is a back view of the device. Fig. 3 is a front view of same, a portion of the bell being broken away. Fig. 30 4 is a view of the holder-plate A.

35 A is a metal plate or stock which may be termed the "holder." It is provided at one end with the holding-points *a*, turned at right angles to the plate, and on the opposite side it has a spring *a'* of suitable character, best formed as a tongue integral with the plate. The other end of the plate or holder is formed with an open-ended slot *a''*.

40 B is the base-plate of the alarm mechanism. It has its forward end turned sidewise to form a stop *b*, and it is provided with a screw-stud *b'*, which slips into the slot *a''* of the holder-plate.

45 A thumb-nut *C*, fitted on the stud *b'*, serves to tighten the base-plate *B* upon and to hold it to the holder-plate *A* in the position and with the firmness required.

50 Carried by the base-plate *B* are the bell *D* and the frame *E* of a suitable clockwork alarm mechanism. This mechanism it is unnecessary herein to show, as it forms no part

in detail of our invention. Its construction being that of the ordinary alarm mechanism, it need not be specifically described in order to fully understand our invention. It is sufficient to say that it consists of the usual spring-operated gearing actuating a striker *e* and put under tension by a winding-key, such as is indicated at *e*, the striker being vibrated by the usual escapement. From the 55 striker projects a pin *e'*, which when held arrests the alarm mechanism.

55 Mounted and adapted to have a sliding movement longitudinally in the base-plate *B* is a tripping-rod *F*. Its forward end passes 60 through and projects beyond the stop *b* of said base-plate. It has a shoulder *f* formed upon it, which when the rod is normally pushed forward or projected engages the pin *e'* of the striker *e* of the alarm mechanism and by 65 preventing its vibration stops the operation of said mechanism. A spring *G* bearing on the tripping-rod serves to hold it projected against the spring-power of the alarm mechanism, which through the pin *e'* tends to 70 withdraw or force it back.

75 The operation of the device is as follows: *H* is a door, and *I* is the stile of the door-casing. The stock or holder-plate *A* (the base-plate *B*, with its alarm mechanism and tripping-rod, being previously removed) is fitted 80 to the casing-stile *I* by pressing the holding-points *a* into the wood, so that the holder-plate is temporarily supported in a horizontal position projecting inwardly from the casing. Then the door is closed, and its edge bearing against plate *A* will force it firmly 85 in place, the spring-tongue *a'* serving to take up slack, thus providing for different spaces existing between the doors and their casings 90 and holding both itself and the door so firmly that the door will not rattle nor will the holder fall out nor can it be pushed out from the outside, because it is back of the stop-bead on the casing-stile. Now the base-plate *B*, 95 with its carried parts, is fitted upon the holder-plate *A* by slipping its stud *b'* into the open-ended and exposed slot *a''* of said holder-plate. It is moved along until the projecting end of the tripping-rod *F* is near to or lightly touches 100 the door, with the stop *b* just back of it and opposing the door. The open-ended slot en-

ables these parts to be readily fitted to the holder-plate, and the elongation of the slot enables the tripping-rod and stop to be brought up to their proper positions, thus compensating for different thicknesses of doors and regulating them to the adjustment or position of the holder-plate. When the base-plate is properly adjusted, it is firmly fixed in position on the holder-plate by tightening up the thumb-nut C. Then the key e is turned to wind up the alarm mechanism, and the latter, though now under tension, is arrested and held inactive by the striker-pin e' being in contact with the shoulder f of the projected tripping-rod. If now the door be forced, the first effect due to the contact of the door with the tripping-rod F is to push said rod back. This will cause it to withdraw its shoulder from engagement with the striker-pin e', which being now free to vibrate will allow the alarm to sound, and the alarm will continue until run down. The second effect is to bring the door up against the stop b of plate B, which thus serves as a lock, keeping the door from being further forced open. The occupant of the room if he desires to hastily investigate the origin of the alarm can by simply giving the thumb-nut a little turn loosen the base-plate B and draw it and its carried parts from the holder out the open-ended slot thereof, thereby releasing the lock and saving time over an operation which would involve an entire removal of the thumb-nut, as would be the case if the slot a² did not open out at the back of the holder. The spring-tongue of the holder holds the door firmly enough to prevent it from being moved inwardly by slight causes, such as wind, and by the arrangement of the tripping-rod to permanently release the alarm mechanism the full value of the latter is obtained, insuring notice to the occupant.

Having thus described our invention, what we claim as new, and desire to secure by Letters Patent, is—

1. In a burglar-alarm and door-lock, the combination of a holder-plate adapted to be seated between the door-casing and the door edge, and having in its rear end an open-ended slot, a base-plate having a stud with thumb-nut, whereby said plate is adjustably and removably fitted to the slot of said holder-plate, said base-plate carrying an alarm mechanism and having a stop on its forward end opposing the door, a slidable tripping-rod mounted in the base-plate with its end extending through the stop and lying in the path of the door movement, and an engagement between said rod and the escapement of the alarm mechanism effective to arrest the operation of the said mechanism when the rod is normally set and to release said mechanism when the rod is pushed back.

2. In a burglar-alarm and door-lock, the combination with the lock and bell, of a holder therefor comprising a plate A provided at one end with an opening for a securing pin

or bolt, and at the other end with separated members having offset points a, a, and an elongated spring a' struck up from the plate at a point intermediate of said separated members and projecting laterally therefrom, substantially as described.

3. In a burglar-alarm and door-lock, the combination with the lock and bell, of a holder therefor comprising a plate A cut away at one end to constitute an open-ended slot a² for a securing pin or bolt, and provided at its opposite end with separated members having offset points a, a, and an elongated spring a' struck up from the plate at a point intermediate of said separated members and projecting laterally therefrom, substantially as described.

4. In a burglar-alarm and door-lock, the combination with the lock and bell, a holder therefor comprising a plate A provided with an opening for a securing pin or bolt, and at one end with a member having an offset point a, and an elongated spring a' alongside said pointed member, said spring being struck up from the plate and projecting laterally beyond the pointed member, substantially as described.

5. In a burglar-alarm and door-lock, the combination of a holder-plate A adapted to be seated between the door-casing and the door edge, a base-plate B, means for securing the base-plate in adjusted position on the holder-plate, an apertured offset portion b on the base-plate arranged to oppose the opening of the door, an alarm mechanism carried by the base-plate, said mechanism including a stop-pin e, a tripping-rod F slidably mounted on the base-plate with its end passing through the aperture in the offset portion b, and lying in the path of the door movement, a spring G secured at one end to the base-plate B and at the other end bearing against the rod F to normally retain the same in outward position, and a shoulder f' on said rod adapted to cooperate with the stop-pin e' of the alarm mechanism to hold the alarm mechanism inactive until the rod is forced inwardly, substantially as described.

6. In a burglar-alarm and door-lock, the combination of a holder-plate A adapted to be seated between the door-casing and the door edge, a base-plate B, means for securing the plate B in adjusted positions on the holder-plate, an apertured offset portion b on the base-plate arranged to oppose the opening of the door, an alarm mechanism carried by the base, said mechanism including a stop-pin e', a tripper-rod F slidably mounted on the base-plate with its end passing through the aperture in the offset portion b and lying in the path of the door movement, and a shoulder on said rod adapted to normally engage the stop-pin e' of the alarm mechanism to hold said alarm mechanism inactive, but to be withdrawn from engagement therewith to release the alarm mechanism when the rod is forced inwardly; substantially as described.

7. In a burglar-alarm and door-lock, the combination with a lock and an alarm mechanism including a stop-pin e' , of a support, a ⁵ slidable tripping-rod F normally projecting outward into the path of the door movement, a spring G for holding the rod in position, said spring being secured at one end to the support and at its free end slidably engaging the rod to permit the movement of said rod independently of the spring, and a shoulder on the rod adapted to normally engage the stop-pin e' to retain the alarm mechanism in- active but when withdrawn from engagement therewith to release the alarm mechanism when the rod is forced inwardly; substan- ¹⁵ tially as described.

In witness whereof we have hereunto set our hands.
